UNITED STATES PATENT OFFICE.

NOAH L. WINE, OF FORT MYERS, FLORIDA, ASSIGNOR OF ONE-FOURTH TO FRANK T. MCNULTY AND ONE-FOURTH TO LUCIUS C. CURTRIGHT, BOTH OF FORT MYERS, FLORIDA.

ELECTRIC DISPLAY-BOARD.

1,141,740.

Specification of Letters Patent.

Patented June 1, 1915.

Application filed November 25, 1914. Serial No. 374,028.

To all whom it may concern:

Be it known that I, NOAH L. WINE, a citizen of the United States, residing at Fort Myers, in the county of Lee and State of Florida, have invented certain new and useful Improvements in Electric Display Boards; and I do hereby declare the following to be a full, clear, and exact description of the invention, such as will enable others skilled in the art to which it appertains to make and use the same.

This invention relates to electric display boards or signs, and one of the principal objects of the invention is to provide an electric display board in which the contact pins are provided with enlarged heads to be covered by a flexible blackboard or sheet which may be written on by a stylus or piece of chalk for depressing the contact pins and for making contact with the cores of electric magnets in circuit with electric light bulbs, so that any figure drawn upon the flexible blackboard will be represented by the electric light bulb on the display board.

25 The foregoing and other objects may be attained by means of the construction illustrated in the accompanying drawing, in which,

Figure 1 is a vertical sectional view taken through a portion of an electric display board made in accordance with this invention, Fig. 2 is a fragmentary rear elevation of the board with the flexible cover or blackboard broken away to show the heads of the contact pins. Fig. 3 is a detail rear elevation with the flexible blackboard or writing surface removed.

Referring to the drawings, the numeral 1 designates a board having a series of apertures 2 therein, and mounted in said apertures are contact pins 3, said pins each having an enlarged flat head 4 which are arranged closely together to form a substantially flat surface. The pins 3 project through a plate 5 and are provided with nuts or washers 6 to limit the movement of the pins backwardly. A spiral spring 7 surrounds each of the pins and the tension of said springs is to hold the pins with the heads out of contact with the board 1 in the position shown in Fig. 1 of the drawing. Electro-magnets 8 are mounted in alinement with the pins 3 and their cores 9 are spaced from the ends of the contact pins 3. A con-

ductor 10 leads from each of the electro-magnets through a plate 11 to a supporting plate 12 to the electric light bulbs 13. Conductors *a* and *b* from a source of electricity supply lead to the plate 12 and to the plate 5, there being a switch *c* in the conductor *b*. 55 A flexible blackboard or cover 14 is placed over the smooth surface of the heads 4 of the contact pins, and when it is desired to display a sign or legend upon the device, a chalk crayon or stylus may be used to trace 60 the letter upon the flexible blackboard 14 and will thus push in the pins 3 to light the corresponding bulb 13 upon the outer side and display the letters upon the blackboard.

From the foregoing it will be understood 70 that when the switch *c* is in closed position, the sign may be written upon the blackboard or flexible member 14 and that the electric light bulbs 13 corresponding to the pins will be lighted and that this sign will be 75 permanent as long as the switch is closed.

Various changes may be made in the details of construction and the relative sizes of the parts, without departing from the spirit and scope of the invention as defined 80 in the claims.

What is claimed is:—

1. An electric display board comprising a series of contact pins mounted in a suitable support and provided with flat extending 85 heads which form a flat almost unbroken surface, a flexible blackboard or screen, and a series of electro-magnets, electric light bulbs and connections whereby when a sign or legend is traced upon the blackboard, the 90 contact pins are pushed in against the cores of said magnets to display the same by the electric light bulb.

2. An electric display board comprising a series of spring actuated contact pins having smooth heads thereon, a flexible blackboard or sheet suspended in contact with said heads, a series of electro-magnets having cores in alinement with said contact pins, electric lights and connections whereby 100 a sign or legend traced upon the blackboard will be reproduced by the electric light.

3. An electrical display board comprising spring actuated contact pins mounted in apertures in a suitable support, said pins having smooth heads adapted to lie in an almost continuous flush surface, a flexible blackboard or sheet suspended in contact

with heads, electro-magnets having their cores mounted in alinement with said pins, electric light bulbs connected to said magnets, connections between the electric lights and the contact pins, a switch in said connections, and means whereby when a sign is placed upon the blackboard or a sheet it will be reproduced in the electric lights by con-

tact of the pins with the electric-magnet cores. 10

In testimony whereof I affix my signature in presence of two witnesses.

NOAH L. WINE.
